UNITED STATES PATENT OFFICE.

HERBERT W. CROOK, OF CHICAGO, ILLINOIS.

MAIL-BAG-CATCHING APPARATUS.

No. 902,977.

Specification of Letters Patent. Patented Oct. 27, 1908.

Application filed October 26, 1907. Serial No. 399,243.

To all whom it may concern:

Be it known that I, HERBERT W. CROOK, citizen of the United States, residing at Chicago, in the county of Cook and State of Illinois, have invented certain new and useful Improvements in Mail-Bag-Catching Apparatus, of which the following is a specification.

My invention relates to the transportation of mail, and has special reference to appliances designed to facilitate the delivery of mail in sacks from a fast moving train without slackening speed. The difficulties attending the successful accomplishment of this seemingly simple procedure are well known, and the apparatus devised to aid in attaining better results have their imperfections. When mail bags are thrown from the train upon the platform, there is danger of injuring both bags and their contents and it has frequently happened that, meeting with some obstacle, the bag has rolled beneath the train there to be cut in pieces by the wheels and the mail matter scattered and destroyed. The appliances in vogue are also liable to cut and abrade the sacks and thus far have proved unreliable or injurious.

It is the chief object of my invention to furnish an improved safe and reliable apparatus for transferring mail sacks from a swiftly moving train to a mail cart and in the accomplishment of this purpose I employ the apparatus which is illustrated in the accompanying drawings which form a part of this application, and in which:

Figure 1 is a side elevation of a mail car equipped with a sack holding device and a special vehicle for receiving the delivered sack; Fig. 2 is an end view of the car and apparatus shown in Fig. 1; Fig. 3 is a side elevation, enlarged, of the sack holder detached from the car, and Figs. 4 and 5 are side and edge views, respectively, of the tripping hooks.

An appliance for the purpose specified must of necessity consist of two interdependent mechanisms; a holding device which will support the mail sack at a point sufficiently remote from the body of the moving car to give clearance for the proper operation of the mechanical contrivance which releases the suspended bag. In my improved mail sack catcher these devices coact in the manner hereinafter set forth so that the sack will be positively delivered within a protective hood or chute so constructed that

the velocity of the bag will be gradually diminished and as the device presents only smooth walls to receive the impact of the filled bag, injury to the said bag will be reduced to a minimum.

Referring to the details of the drawing, the numeral 10 indicates a mail car, and 11 the side opening or doorway. Upon opposite sides of this opening are fixed apertured lugs or eyes 12, which form supports for a removable frame or bag holder, the arrangement of the eyes permitting the frame to be attached to either side of the door according to the direction in which the train is moving. 65 The holding frame consists of an upright member 13 furnished with downwardly projecting lugs forming pintles 14, which fit the apertures in said eyes 12. From each end of the member 13 project arms 15, 16, the lower arm 16 being shorter than the upper arm for a purpose which will hereinafter appear. The arms 15, 16, are secured to the upright member in any suitable manner, and the junctions are strengthened by braces 17, which 70 render the frame vertically rigid. At the end of the lower arm, and at a corresponding point upon the upper arm are headed projections 18, which serve as engaging lugs for the looped ends or eyes 19, formed at 75 the extremities of the arms 20, of a bifurcated tie or brace 21. This member is intended to prevent the frame or holder from being swung laterally, and it acts especially as a tie to resist the impact of the tripping means hereinafter described. The said tie is formed of a single rod the inner end being twisted and turned downward to form a hook 22 which engages an eye 23 fixed to the door side. The hook is locked in position 80 by an angle piece or latch 24 pivoted on a bolt 25 so that it can be swung aside to allow the hook to be removed. A similar latch 26 is used to secure the holding frame in 85 position.

The outer end of the upper arm 15 is turned at a right angle to form a flange 27, and to this flange is pivoted a block 28, a lug 29 fixed in the side of the block forming the pivot. The block 28 supports a swivel 105 member or trip 30 formed of a flat bar, the lower end formed into a hook 31, and the upper end reduced in size and provided with a screw 32, which passes freely through said block and is furnished with a flanged nut 33, 110 which fit within a channel 34 cut in the upper face of the block, and when the channel

is engaged by the said nut the latter is prevented from turning. By this construction the trip 30 is adjustable relatively to said block, a lock nut 35 retaining the flanged nut 33 in the desired position upon the screw 32.

The lower arm 16 is provided with an extension which consists of a lever 36 pivoted at 37, to the end of said arm, the free end of the lever having a flange 38 similar to the flange 27 of the upper arm and in vertical alignment therewith when the lever 36 is horizontal. To this flange is pivoted a block and swiveled hook, similar in every respect to the block 28 and hooked member 30, except that the parts are reversed so that the hooked member projects upward instead of downward. To the inner end of the said lever 36 is attached a cable or light rod 39, its upper end being connected to a spring 40 which is fastened to the upper arm 15. The object of the swiveled hooks 31 is to suspend the mail bag 41, which is furnished with rings 42, in its ends, and these rings engage the said hooks 31. The tension of the spring 40 upon the lower hook will be sufficient to prevent a deviation of the bag from a perpendicular by the force of the air currents and swaying of the car. A clip 36^a is secured to the inner end of the lower frame arm 16, and is offset from the arm sufficiently to receive the inner end of the lever 36 when in extended position, thus preventing excessive strain upon the pivot 37 when the coacting member strikes the tripping member, in the manner hereinafter described. The bag being thus suspended free from the car it will be necessary to supply some means for dislodging it as the car passes a station and to do this with certainty and without injury to the bag or its contents I provide a special apparatus consisting of a frame 43, supported upon ground wheels 44, and provided with a tongue 45. Upon the frame of the vehicle or truck is mounted a bed or body 46, inclosed upon all sides except the front, which is provided with an opening 47, furnished with flaring sides 48, thus forming a chute or funnel sufficiently capacious to receive the largest mail sacks. The roof of the body is curved as indicated at 49, and a door 50 gives ready access to the interior. The vehicle is anchored to resist the shock which will be proportioned to the speed of the train and the weight of the sack caught therein. I immobilize the apparatus by means of suitable rods 51 provided with hooks 52 for engagement with the frame of the truck, the lower ends supplied with eyes 53 through which are passed securing devices 54, formed by bending suitable rods to form one or two coils 55 about the middle point and having the ends bent into hooks 56, which engage eye bolts 57, fixed in the platform 58. The coils 55 furnish sufficient resiliency to hold the hooks 56 in engagement

with said eye-bolts but will permit of their disengagement when the truck is to be removed.

The method of operating the apparatus is as follows: The frame having been set in the position shown and a mail bag hung upon the swivel hooks 31, the bag is ready for delivery. Care must be taken that the openings of the hooks which support the bag look towards the direction in which the train is moving. The station which is to receive the mail, prepares for the train by placing the truck in the position shown in the drawings and anchoring it securely in the manner shown. The eye-bolts 57 being permanent fixtures the truck will always be positioned properly to receive the sack. Care must be taken to face the flaring opening in the direction of the approaching train. The height of the upper and lower margins of the chute are so arranged that they will engage the hooked trips 30 and the momentum of the moving frame will cause a sufficient impact to rock the said members upon their centers thus releasing the sack which will be carried with some force against the curved inner surface of the cover, and by this means the momentum will be gradually lessened and the force with which the sack will strike the floor will not be sufficient to cause injury to the contents. As the trips 30 are thrown backwards they will clear the body of the truck and their swivel connections with the blocks 28 permit their hooks to be set in either direction according to the train movement. The frame can be swung upon the pintles 14 so as to be parallel with the side of the car or may be entirely removed from engagement with the eyes 12, and stored within the car.

Having thus described my invention what I claim as new is:

1. An apparatus for the purpose specified, including a frame attached to the side of a car, means for detachably supporting a mail bag on said frame, a receiving device coacting with said frame, said device consisting of a receptacle mounted upon traction wheels and having an opening adapted to admit said mail bag, the margins of said opening adapted to engage the supports of said bag.

2. An apparatus for the purpose specified, including a frame attached to the side of a car, means for detachably suspending a mail bag to said frame, a receiving apparatus coacting with said frame, said apparatus consisting of a receptacle mounted upon traction wheels and having an opening adapted to admit said bag, a curved surface arranged to receive the impact of the released mail bag, and means for anchoring said apparatus.

3. An apparatus for the purpose specified including a frame removably attached to the side of a car, a tripping device for detach-

ably suspending a mail bag to said frame, a receiving receptacle mounted upon traction wheels and adapted to engage said tripping device for the purpose of disengaging said bag, and means for gradually lessening the momentum of the released bag.

4. A device for the purpose specified, including a frame attached to the side of a car, a tripping device for detachably suspending a bag from said frame, a receptacle arranged in the path of the said frame, said receptacle mounted upon traction wheels and coacting with the tripping device, to detach said bag, means for gradually lessening the momentum of the released bag, and means for anchoring said receptacle.

5. A device for the purpose specified, including a frame attached to the car, swiveled supports for a mail bag, a receiving truck mounted upon wheels, a body supported upon the truck and having an opening to receive a mail bag, the margins of said opening adapted to engage said swiveled supports when the car is in motion, and means for anchoring said truck in the path of said frame.

6. A device for the purpose stated, including a frame removably hinged to the side of a car, tripping members carried by said frame and arranged to support a mail bag, a coöperating receiving truck comprising a body mounted upon wheels, a flaring aperture for the body, and means for securing said truck to the station platform.

7. An apparatus for the purpose specified,

including a frame adapted to be attached to the side of a car, tripping devices for detachably supporting a mail bag, a receiving device consisting of a receptacle mounted upon traction wheels, a curved wall forming the upper and rear side of the receptacle, and means for removably anchoring the device.

8. An apparatus for the purpose specified, including a frame adapted to be attached to the side of a car, tripping devices for detachably supporting a mail bag, a receiving apparatus consisting of a receptacle mounted upon traction wheels and having a flaring opening, a curved top for the receptacle, a door, and means for anchoring the apparatus.

9. An apparatus for the purpose stated, including a frame having hinged connection with the side of a car, means for immobilizing said frame, swiveled tripping devices for detachably suspending a mail bag to said frame, receiving means for said bag, said means consisting of a wheeled truck, a body supported on the truck, said body arranged in the path of the frame, adapted to engage said swiveled tripping devices, a curved top for the body, a door, and means for removably anchoring said truck.

In testimony whereof I affix my signature in the presence of two witnesses.

HERBERT W. CROOK.
